UNITED STATES PATENT OFFICE.

WILLIAM H. CLEVELAND, JR., OF SUPERIOR, WISCONSIN.

GAGE ATTACHMENT FOR DRAWING-KNIVES.

1,080,419.

Specification of Letters Patent.

Patented Dec. 2, 1913.

Application filed March 26, 1913. Serial No. 756,920.

To all whom it may concern:

Be it known that I, WILLIAM H. CLEVELAND, JR., a citizen of the United States, residing at Superior, in the county of Douglas 5 and State of Wisconsin, have invented new and useful Improvements in Gage Attachments for Drawing-Knives, of which the following is a specification.

The present invention relates to gage attachments for drawing knives.

In carrying out my invention it is my purpose to provide a detachable gage which may be readily positioned upon any ordinary drawing knife for regulating the 15 depth of the cut of the knife as well as for guiding the knife to its work.

A still further object of the invention is to provide a gage of this class which is longitudinally adjustable so as to compensate 20 for work of varying sizes and which also permits of the tilting or inclination of the knife as well as sustaining the said knife when employed for beveling edges of materials.

With the above recited objects in view 25 and others of a similar nature which will appear as the description of the invention progresses, the improvement resides in the novel construction and combination of parts set forth in the following description and 30 falling within the scope of the appended claims.

In the drawings, Figure 1 is a perspective view of a portion of a drawing knife with my improvement attached. Fig. 2 is 35 a bottom plan view of the same. Fig. 3 is a sectional view upon the line 3-3 of Fig. 2. Fig. 4 is a sectional view upon the line 4-4 of Fig. 2.

Referring now to the drawings in detail 40 the numeral 1 designates the blade of an ordinary drawing knife, and 2 the gage attachment for the knife. The gage comprises essentially a pair of elements which may be designated by the numerals 3 and 4 respectively. These elements are each of a similar formation and comprise a lower or base portion 5, the upper face of which is flattened, while the longitudinal sides of the said base members are beveled or inclined toward 45 each other. The rear portions of each of the members 3 and 4 are extended vertically as at 6 and connected with the said vertical extensions are the flanges 7 which overlie the rear portion of the flattened upper faces 50 of the base members. These overlying flanges 7 are each provided with threaded 60 openings, the same adapted to receive thumb screws 8 whereby the said members 3 and 4 are sustained upon the drawing knife 1. The outer extremities of the base portions 65 of the members 3 and 4 are also provided with threaded openings, the said openings adapted to receive threaded bolts 9. The bolts 9 are each provided with an annular groove 10 within which is received the arms 65 provided by the bifurcated ends of a gage plate 11. The portion of the bolts above the annular depressions is preferably squared or angular as designated by the numeral 12, while the bolt above the said squared or 70 angular portion is provided with a reduced threaded portion or stud 13.

The numeral 14 designates a binding collar which is provided with a squared bore and which is adapted to engage with the 75 squared portions of the bolts, and the numeral 15 designates a milled nut which engages with the threaded stud or extension of the bolt and which binds against the collar 14 to force the said collar tightly into 80 engagement with the gage plate 11.

From a construction as just described, it will be noted that by rotating the collar 14, of each of the bolts 9, the said bolts will be raised or lowered upon the members 3 85 and 4, thus elevating or lowering the gage plate 11. It will be further noted that by partially unscrewing the nuts 15 to relieve the pressure of the collars 14 upon the gage plate 11 as well as by loosening the thumb 90 nuts 8, the members 3 and 4 may be spread either toward or away from each other so as to engage with the sides of the work to be operated upon by the knife 1. It will be still further noted that by having the 95 sides of the members 3 and 4 inclined or beveled the knife may be caused to assume an inclination when the corners of work are to be operated upon and from the above description taken in connection with the accompanying drawing, the simplicity of the construction, the advantages thereof, as well as the cheapness of the manufacture of the device, will it is thought be appreciated by those skilled in the art to which such inventions appertain, it being merely necessary to add that the gage plate 11 being arranged forward of the knife 1 will not only serve to limit the depth of the cut to be made by the knife, but will also in conjunc- 100 105 110

tion with the members 3 and 4 serve as a guide for the knife during the working of the knife.

Having thus described the invention, what I claim is:

1. An attachment for drawing knives comprising a pair of members detachably connected with the knife, means whereby the members may be adjusted toward or away from each other and an adjustable gage plate carried by the members and arranged forward of the knife.
2. A gage for drawing knives comprising a pair of members removably and adjustably secured upon the knife and projecting beyond the cutting edge thereof, and a vertically and longitudinally adjustable gage plate connected with the forwardly extending portions of the said knife.
3. In combination with a drawing knife, of a gage therefor, said gage comprising a pair of members each having one of their ends upset and provided with a flange which overlies the said member, thumb screws for the overlying flanges and adapted to engage the blades of the drawing knife to retain the same upon the members, each of the members having its extremity provided with a threaded opening, a threaded bolt within each of the openings, each of the threaded openings being provided with an annular depression, a gage plate having its opposite ends bifurcated and engaging within the annular depressions of the bolts and means connected with the bolts for compressing the gage plate to retain the same immovably within the annular depressions of the bolts.
4. An attachment for drawing knives comprising a pair of substantially J-shaped members, means provided upon the upper

and shorter arms of the J-shaped members for adjustably sustaining the said members upon the drawing knife, the sides of the lower arms of the members being inclined toward the central portion of the base thereof, the said lower arms being provided with threaded openings, threaded bolts within the openings, each of the said bolts being provided with an annular groove, a flattened gage plate having its opposite face bifurcated and engaging within the annular grooves, and means provided upon the bolts for engaging with the gage plate for immovably sustaining the same upon the bolts.

5. A gage attachment for drawing knives comprising a pair of substantially J-shaped members, the lower arms of the said J-shaped members having their sides inclined toward each other, thumb nuts upon the upper arms and engaging with the drawing knife, the lower arms being provided with threaded openings, threaded bolts engaging the openings, the said bolts being provided with an annular depression, a gage plate engaging within the annular depression, the said bolts being further provided with angular portions projecting above the said depressions, a collar having an angular bore engaging with each of the angular portions of the bolts, each of the bolts having a threaded stud projecting above their inclined portions and a nut co-acting with each of the studs, substantially as and for the purpose set forth.

In testimony whereof I affix my signature in presence of two witnesses.

WILLIAM H. CLEVELAND, JR.
